ATTORNEYS

UNITED STATES PATENT OFFICE.

JOHN Q. SHERMAN, OF DAYTON, OHIO.

FILE CABINET.

Application filed January 21, 1924. Serial No. 687,428.

My invention relates to cabinets in which are mounted suitable holders for cards, folders or envelopes, said holders being individually available.

5 In devices of the character noted, the essential points are compactness, simplicity and speed of operation, and generally the provision of a quickly available and readily operable filing system, whereby entries may 10 be rapidly made on individual cards, or slips carried in envelopes or folders.

The general plan of my invention is to provide the holders with offset finger holds which bear designation numerals and individual entry elements carried on the holders, said entry elements also having offset designation indicia.

It is further my object to provide for 20 holders which are pivoted within the cabinet and are to be rocked upward to a position to free the individual entry elements for removal, said holders being automatically held up, and guided back when they have served their purpose.

25 In connection with the cabinet features of the device, it is my object to provide for a top lid or cover which will swing down out of the way, and preferably to provide one of the sides of the cabinet to swing away 30 also, thereby exposing a chart, on its inner face, and at the same time providing a desk upon which the individual entry elements can be placed. By preference I also provide for snapping the lid to the underside of the 35 cabinet.

I accomplish my objects by that certain construction and arrangement of parts to be hereinafter more specifically pointed out and claimed.

40 In the drawings:

Figure 1 is a perspective view of the cabinet when closed, showing in dotted lines some of the interior arrangements.

Figure 2 is a section taken vertically 45 through the device lengthwise of the holders.

Figure 3 is a sectional detail showing the snap stop to hold the holders from falling inwardly of the cabinet.

Figure 3^a is a modification of the form 50 of stop shown in Figure 3.

Figure 4 is a side elevation of one of the holders.

Figure 5 is a perspective view showing the cabinet in use.

Figure 6 is a view in side elevation of one 55 of the holders filled with cards.

Figure 7 is a view of a fragment of the chart or index.

Referring to the cabinet structure primarily, it will be noted that I provide a cabinet 60 having a base 1, end walls 2, 2, and permanent side wall 3, and a hinged side wall 4. The handle for carrying the cabinet from place to place will be mounted, say, on one of the end walls, as shown at 5.

65 The lid 6 of the box is hinged to the wall 4, and swings away with it, and a snap fastener 6^a, or its equivalent will be placed on the top of the lid, so that when swung open with the side wall, it can be moved up underneath said side wall and snapped in place as in the slot 6^b, to be out of the way.

70 There will be an arc-shaped guiding and supporting arm for the side wall as shown at 4^a, which will provide in a familiar 75 manner for limiting the downward swing of the side wall and supporting it on the cabinet, for use as a writing desk or support. As shown also, it is preferable to mount the chart or index 7 on the inner face of the side 80 wall so that it will be exposed to the operator when using the device.

85 The lock for the box will be placed on the lid as at 8, so as to render it unavailable to those not authorized to inspect its contents.

Within the box, mounted between ears 9, extending inwardly from the one end wall, is a spindle or rod 10, on which the holders are mounted. The holders may take a wide 90 variety of forms, and I have illustrated but one, in which preferably a thin metal plate 11 is provided having an ear 12 for engaging over the spindle and having its lower edge flanged upwardly at 13, to support the 95 lower edges of the individual entry elements, and a return-bent flap 14, extending from the back end to a point fairly close to the front, to prevent the cards from falling out sidewise, and from falling out through 100 the back of the holder. The front and top of the holders are exposed to permit ready removal of the entry elements.

I have illustrated as entry elements a series of cards, although envelopes or folders 105 could be used. The cards 15, in the form illustrated, have tabs 16 which are arranged in offset relation to each other as shown in

the drawings, thereby exposing all tabs to view. I have lettered the tabs on the cards, and numbered the holders, but it will be understood that this system of marking can be modified to suit the individual purpose.

The holders have on their upper edges the finger holds 11^a, which bear the identification numbers, and serve as handles whereby the holders are rocked on the mounting spindle.

The right side wall 2 is arranged so that the top edge of a holder will strike the side wall as indicated at 11^b when the holder is elevated. Also on or near the top edge of each of the holders in the form shown in Figure 3, I press out a knob 17, or provide some other form of abutment, so that when a holder is pulled to its upper position, as shown in dotted lines at 18 in Figure 2, the normal inner end of the holder will lie over the knob on the next holder to it, thereby preventing the holder from falling back into the cabinet, and also serving to guide it into place when it is desired to force it down. The section in Figure 3^a shows a reversed arrangement with a similar function in which the knob 17^a is formed near the right hand end of a plate portion 11, to snap over the top of an adjoining plate 11.

By making the holders high enough to preserve "inter-leaved" contact with any holder which may be elevated to a position of abutment with its normal top edge against the side wall of the box and using the holder knobs or catches, it will be evident that it will always be easy to rock a holder back into position.

The index or chart may be arranged with names as at 20, in alphabetic relation, and after each name will be entered the number of the holder and letter of the card, folder or envelope, upon or within which the name will be found.

Thus the name W. G. Frank is in holder number 1, letter A card. The name F. L. Merkle is in holder 12, letter D card.

In use the operator will open the cabinet and thus will have his chart before him, and a writing place for making entries. He will take each name in turn and first get from the index where the name card is to be found, and will then grasp the holder of the right number and lift it up until it will not come any further. The holder will then stay in place, but will not be out of interleaved relation to the other holders. The individual card designation tabs will be exposed, however, as the cards are thrust in between the bodies of the holders and the flaps 14 thereof, leaving their tabs exposed. The individual card is then withdrawn, placed on the writing support, and the desired entry made, after which it will be replaced, and the holder thrust down, throwing it into correct line for falling into place.

This is naturally a very simple operation and provides all of the features of a very quickly available and complete filing system for a large number of individual entry elements. As shown the finger holds on the 70 holders will be arranged in offset relation, and in as many rows as may be found convenient, so that there is plenty of finger space to permit the operator to grasp and rock the holder.

The filing cabinet will be provided with a complete set of cards and holders, and the necessity of arranging the cards in alphabetical relation is done away with, so that the operator in inserting a new card, can 80 select some convenient empty card, and note down on the chart the number and letter of said card.

Having thus described my invention, what I claim as new and desire to secure by 85 Letters Patent, is:—

1. A device of the character described comprising a cabinet, a series of holders pivotally mounted in said cabinet, said holders having finger holds and index notations 90 thereon, said notations exposed when the cabinet is open, and individual entry elements removably carried within the holders, said individual entry elements having exposed index notation thereon, said pivotal mounting 95 adapted to permit individual holders to be swung up away from the others, thereby exposing the individual entry elements for withdrawal.

2. A device of the character described 100 comprising a cabinet, a series of holders, means for pivotally mounting said holders, adapted to permit individual holders to be swung up from the other holders, and means for automatically retaining a holder against 105 falling back into the assembly of holders by gravity after it has been swung up.

3. A device of the character described comprising a cabinet, a series of holders, means for pivotally mounting said holders, 110 adapted to permit individual holders to be swung up but not so far as to be out of interleaved engagement with the other holders, and means for automatically retaining a holder against 115 falling back into the assembly of holders 115 of holders by gravity after it has been swung up.

4. A device of the character described comprising a cabinet, a series of holders, means for pivotally mounting said holders, 120 adapted to permit individual holders to be swung up from the other holders, and means for automatically retaining a holder against falling back into the assembly of holders by gravity after it has been swung up, said 125 means comprising elements on the holders themselves adapted to present abutments to the edges of adjacent holders.

5. A device of the character described comprising a cabinet, a series of holders, 130

means for pivotally mounting said holders, adapted to permit individual holders to be swung up from the other holders, and means for automatically retaining a holder against falling back into the assembly of holders by gravity after it has been swung up, said means comprising knobs formed near the top edges of the holders and adapted to engage the lower edges of swung-up holders, when same are in swung-up positions.

6. A device of the character described comprising a cabinet, a series of holders pivoted therein so as to swing upwardly of the cabinet, and a closure for the cabinet comprising a side wall and lid thereof articulated together, and the side wall articulated to the cabinet, said side wall having supporting means with relation to the cabinet to retain it in position for a writing support.

7. A device of the character described comprising a cabinet, a series of holders pivoted therein so as to swing upwardly of the cabinet, and a closure for the cabinet comprising a side wall and lid thereof articulated together, and the side wall articulated to the cabinet, said side wall having supporting means with relation to the cabinet to retain it in position for a writing support, and means for holding the lid in position turned under the side wall and fastened thereto, so as to remove it as an obstruction.

8. A device of the character described

comprising a cabinet, a series of holders pivotally mounted in said cabinet, said holders having finger holds and index notations thereon, said notations exposed when the cabinet is open, and individual entry elements removably carried within the holders, said individual entry elements having exposed index notations thereon, said pivotal mounting adapted to permit individual holders to be swung up away from the others, thereby exposing the individual entry elements for withdrawal, and a chart for the identification of the holders and individual entry elements within the holders, mounted on the cabinet.

9. A device of the character described comprising a cabinet, a top lid movably mounted to open the top of the cabinet, a side wall also movably mounted to swing downwardly so as to expose its inner face, a chart on the side wall inner face, and a series of holders in the cabinet, means for permanently retaining them in the cabinet, said means being adapted to permit the holders to swing in a vertical plane out of the top of the cabinet, said holders having tabs extending upwardly therefrom, and adapted to be grasped in the fingers of the operator, means for retaining the holders in swung out position, and identifying marks on said tabs exposed to the view of the operator when the lid is moved away.

JOHN Q. SHERMAN.
